UNITED STATES PATENT OFFICE.

ISAAC TAYLOR, OF NEW YORK, N. Y.

FROSTING PLATES OF GLASS.

Specification of Letters Patent No. 8,519, dated November 11, 1851.

To all whom it may concern:

Be it known that I, ISAAC TAYLOR, of New York, in the county and State of New York, have invented a new and useful Machine for Frosting and Embossing Plates of Glass; and I hereby declare that the following is a full and exact description.

To enable others to make and use my invention I proceed to describe its construction and operation, reference being had to the annexed drawings which make part of this specification.

Figure 1 represents the machine as it is made for ordinary use. It is about ten feet 15 long and four or five feet wide. Fig. 2 end of the same. Fig. 3 transverse section.

The trough is placed on a couple of rockers which are attached to it and these are set upon other rockers reversed and the two 20 are held in their relative position by permanent dowels in the bed rockers working in a slot made in the rockers of the trough.

There is a standard at one or both ends of the trough at the top of which is attached, 25 by a pin or pivot, a connecting rod which may be moved by hand or by a crank. The object is to rock the trough back and forth. When figures are to be embossed on glass by this process, they are first cut or ground out 30 in intaglio. The sheets of glass are then

laid on the bottom of the trough and secured in place (if need be) with the intaglio figures up. Then a quantity of pebbles about the size of hickory nuts, or filberts, and of all less sizes, with siliceous sand, is put over the glass and water poured upon it so that it will make a thin or cream-like mud of the sand. The machine is then rocked back and forth slowly just fast enough for the sand and pebbles to roll from 35 side to side by the motion and this is continued from twenty minutes to an hour when the glass will be found to be embossed and frosted.

It is well, and sometimes necessary, to 40 change the position of the glass, turning each plate one quarter round, to make the frosting equal. The process for plain glass is the same.

What I claim as my invention and desire 45 to secure by Letters Patent is—

The use of a rocker containing pebbles, sand and water for the purpose of frosting plates of glass or embossed work as above described.

ISAAC TAYLOR.
